DESIGN FOR A COMBINED PINCUSHION AND SPOOL HOLDER

Mamie B. McCall, St. Joseph, Mo.

Application April 29, 1946, Serial No. 129,073

Term of patent 7 years

(Cl. D3—19)

To all whom it may concern:

Be it known that I, Mamie B. McCall, a citizen of the United States, residing at St. Joseph, in the county of Buchanan and State of Missouri, have invented a new, original, and ornamental Design for a Combined Pincushion and Spool Holder, of which the following is a specification, reference being had to the accompanying drawing, forming part thereof.

Figure 1 is a front elevation of a combined pincushion and spool holder showing my new design. Fig. 2 is a top plan view of the same.

I claim:

The ornamental design for a combined pincushion and spool holder, as shown.

MAMIE B. McCALL.
